MAGNETIC MOUNTING DEVICE FOR
GUN SIGHTS

Keith R. Detrich, Prairie Village, Kans., assignor of
one-half to Otto O. Royer, Cleveland Heights, Ohio
Filed Sept. 3, 1958, Ser. No. 758,769
9 Claims. (Cl. 33—50)

This invention relates to a mounting device for telescopic gun sights, and more particularly to a mounting device which utilizes the magnetic force of permanent magnets as the sole means for holding the telescopic sight in its proper position on the gun.

Another object of this invention is to provide a mounting device for telescopic sights which permits rapid removal and replacement of the sight without affecting a preset alignment of the sight with the bore of the gun.

A still further object of this invention is to construct a magnetic mounting device for gun sights that will permit the sight to become dislodged from its operative position on the gun should the sight receive a severe jolt, as by rough usage, thus avoiding possible damage to the sight or causing it to become misaligned with the bore of the gun when replaced in its operative position.

A still further object of this invention is the provision of a mounting device for telescopic gun sights which requires a minimum of time and skill in the preparation of the gun for receiving the mounting device.

A still further object of this invention is to provide a magnetic mounting device for gun sights with a built in keeper for protecting the magnets against loss of residual magnetism when the sight is not in position on the gun.

Another object is to provide a means for securing a telescopic sight to a device for mounting the sight on a gun, which means is in the nature of a semi-universal joint to facilitate adjustment of the sight to a position in alignment with the bore of the gun.

Another object is to provide a magnetic mounting device of the type described which includes a keeper to protect against loss of magnetism and which also utilizes a separator strip of non-magnetic material between the keeper and permanent magnet for reducing the strength of the magnet when not in use to protect against adherence of foreign particles thereto.

A still further object is to provide a gun sight mounting device that has sufficient magnetic attraction to retain the same on a gun during normal use of the gun but which is quickly and easily removable from the gun by pulling it with the hand.

Another object is to provide a mounting device of the type described in which a permanent magnet is retained in position adjacent the upper end of a pair of pole pieces by a block of non-magnetic material fixed to said pole pieces.

Another object is to provide a magnetic mounting device for gun sights in which magnet and pole pieces of substantially the same width are employed whereby a flux path of minimum reluctance is established when the pole piece is in position on the gun.

Other objects will be apparent from the following description and from the drawings in which:

FIGURE 1 is a side view showing a telescopic sight mounted on a gun by means of the magnetic mounting device comprising the present invention, the gun being fragmentarily shown.

FIGURE 2 is an enlarged end view of the mounting device and a fragmentary portion of the telescopic sight and gun.

FIGURE 3 is a side view of FIGURE 2 showing a portion of the mounting device cut away.

FIGURE 4 is a cross sectional view taken on line 4—4 of FIGURE 3.

2

FIGURE 5 is a diagrammatical view, illustrating the principal magnetic circuit when the sight is mounted on the gun.

FIGURE 6 is a diagrammatical view illustrating the principal magnetic circuit when the sight is removed from the gun.

The telescopic sight 10 illustrated in FIGURE 1 is of a conventional telescope type and has a cylindrical tube 11 secured substantially in parallelism with the bore 10 through the barrel or receiver 12 of a gun by a pair of identical magnetic mounting devices 13 which comprise the present invention. Since the mounting devices are identical, the following description is confined to one but is applicable to both.

15 The magnetic components of the mounting device, which comprise a magnet assembly, consist of a keeper 14 of magnetic material, a separator plate 15 of non-ferrous material, a retaining block 16 of hard non-magnetic material, a permanent magnet 17, and a pair of soft magnetic steel pole pieces 18.

To retain the keeper 14, separator plate 15, and pole pieces 18 in assembled position, a pair of non-magnetic retainer plates 20 are silver soldered to the keeper and the pole pieces. The permanent magnet 17 is retained 25 in position by the retaining block 16 which is pinned to the pole pieces by roll pins 21.

The keeper 14, separator plate 15, permanent magnet 17, and retaining block 16 have aligned bores 23, 24, 25, and 26 therethrough, respectively. A non-magnetic bushing 27 is located within the bores and is held in position by silver soldering to the keeper 14. The bushing has an internal thread 28 therethrough into which is threaded a non-magnetic centering pin 29 having a tapered extension 30. The pin 29 has a drilled hole 31 therethrough and a screw driver slot 32 at one end.

35 The pole pieces 18 have arcuate openings 34 formed on their under sides for intimately fitting and contacting the curved surface of the gun barrel upon which the device is to be mounted. The lower side of the retaining block 16 is likewise arcuately formed as at 35 but at a slightly larger radius than the arcuate portion of the pole faces so that there is a small space 36 between the retaining block and the gun barrel 12 when the mounting device is in position on the gun.

45 The upper side of the keeper 14 is arcuate as viewed in FIGURE 2 and has a groove or channel 40 therein which in cross section is formed on a radius 41 which is preferably in the neighborhood of twice the diameter of curvature of the arcuate upper side of the keeper. On each side of the groove 40 there are short cylindrical portions 42.

Fitted within the groove 40 is a ring 43 having a longitudinal split 44. The outer surface of the ring is curved in cross section to the same radius 41 as the groove 40.

55 The inner diameter of the ring is such as to fit the outer diameter of the telescopic sight 10. The ring 43 is retained in position on the keeper by a strap 46 which has an arcuate portion 47 and radially extending portions 48. The arcuate portion 47 has a groove 49 corresponding to the groove 40 in the keeper and which groove in cross section is formed to the same radius 41 for closely fitting the outer surface of the ring 43. The radial portions 48 overlie the side plates 20 and are secured thereagainst by screws 50 threaded into keeper 14. The ring 43 and strap 46 are so proportioned that tightening of the screws 50 causes the strap to compress the ring tightly against the telescopic sight for firmly clamping the same to the mounting device, it being understood that there is sufficient initial clearance between the radial portions 48 and the retainer plates 20 for this purpose.

60 65 70 75 80 85 90 95 By forming the outer surface of the ring and the complementary inner surfaces of the strap 46 and keeper 14

on a radius which is approximately twice the diameter of such surfaces, a semi-universal swiveling action of the ring 43 within the channel portions of the keeper and strap is obtained when the sight is loosely held by the two mounting devices when the latter are in position on the gun preparatory to tightening the straps. In other words a semi-universal connecting means is provided for connecting the sight 11 to the mounting devices 13. Thus, when both of the mounting devices 13 have been fitted to a gun barrel, each device has a set position on the barrel determined by the fit of arcuate openings 34 of the pole face on the gun barrel and the fit of the tapered extension 30 of the pin 29 in the tapered locating hole 52 in the gun barrel. When the two mounting devices are in such set positions, if there is any misalignment of the longitudinal axis of the ring 43 of the one device with the longitudinal axis of the ring of the other device, the rings will swivel as necessary within the respective straps 46 and keepers 14 so that their longitudinal axes will become aligned and permit firm clamping of the telescopic sight as the screws 50 are tightened.

It has been found preferable to provide only the semi-universal action afforded when the radius 41 is approximately twice the diameter of the outer surface of the ring since the clamping action on the sight is more firm and there is less tendency for the sight to swivel or shift within either of the devices when the gun is fired or roughly handled.

To prepare a gun for the mounting devices, the centering pin 29 of each device is retracted so that the arcuate sections 34 of the pole pieces may rest firmly on the gun barrel. With the sight in position, the two devices are then aligned and properly located on the gun barrel. When the proper location of each device has been determined, the straps 46 and rings 43 and the sight 11 may be removed and a drill or other suitable tool inserted through the drilled hole 31 to mark the center location for the tapered hole 52 to be formed in the gun barrel for each device. After the tapered hole has been formed, the mounting device is put back into its proper position and the centering pin 29 is threaded toward the gun barrel until the tapered extension 30 seats in the tapered hole 52. At such time the tapered extension 30 and the arcuate openings 34 of both pole pieces for each mounting device will be in contact with the gun barrel and will effectively locate the mounting device in a fixed predetermined position. Since the pole pieces have relatively little thickness the actual area of contact with the gun barrel is relatively small and thus there is less chance that nicks or foreign matter will cause improper seating of the pole pieces against the gun barrel.

After both tapered holes 52 have been formed, and the mounting devices placed in position on the gun barrel with the centering pins 29 properly adjusted to seat in the tapered holes, the rings 43 may be slipped over the telescopic sight 10 and placed in position in the groove 40 of the respective keeper 14. The straps 46 are then placed in position and the screws 50 tightened to firmly clamp the telescopic sight onto the mounting devices.

Each mounting device is retained in its position on the gun barrel by magnetic attraction. Thus, as diagrammatically illustrated in FIGURE 5, when the mounting device is in position on the gun barrel, the magnetic flux generated by the permanent magnet 17 passes through the magnet and one pole piece and then passes through the gun barrel and the other pole piece and back to the magnet. Because of the intimate contact of the pole pieces with the gun barrel, the flux path shown in FIGURE 5 is the one affording the least reluctance and hence and hence provides the greatest amount of magnetic flux when the mounting device is in position.

The keeper is desirable for preserving the residual magnetism when the device is removed from the gun to be stored over long periods of time. When the mounting device is removed from the gun barrel, the path of

greatest flux is as diagrammatically illustrated in FIGURE 6 since the path of least reluctance is from the magnet 17 through the pole piece 18, through the non-magnetic separator strip 15, the keeper 14, the other pole piece 18, and back to the magnet.

The separator strip acts as a small air gap which provides enough reluctance to cause the magnetic flux to follow the path illustrated in FIGURE 5 when the mounting device is in position with the pole piece in contact with the gun barrel, and yet permits passage of the magnetic flux therethrough so that the flux path will be as illustrated in FIGURE 6 when the mounting device is removed from the gun barrel and permits the keeper 14 to help retain the residual magnetism of the magnet 17.

The separator strip also affords a gradual transition of the flux path from that shown in FIGURE 6 to that of FIGURE 5 when placing the telescopic sight in position on the gun and thus minimizes the snap action of the magnet as it is attracted to the gun barrel when approaching the same. This permits steadier and more accurate placement of the sight in its proper position on the gun and lessens the chance of nicking or damaging the parts.

It will be seen that with the present invention a telescopic sight may be quickly attached or removed from a gun. To attach the same, the telescopic sight, with the mounting devices firmly clamped thereto as previously described, is simply placed in position on the gun barrel with the centering pins 29 seated in the tapered holes 52. Magnetic attraction then holds the mounting devices and the attached sight firmly in the preset fixed position. To remove the sight, it is simply grasped by the hand and pulled off the gun barrel.

Although a preferred embodiment of the invention has been illustrated and described, it is obvious that many changes may be made in the detail construction without departing from the invention as covered by the following claims.

I claim:

1. A mounting device for gun sights comprising a magnet assembly including a permanent bar magnet and a pole piece at each end of the magnet, the lower ends of said pole pieces being adapted to seat on a gun and being shaped to engage in intimate contact therewith when in position on said gun so as to provide a path with said gun for magnetic flux generated by said permanent magnet, means for attaching a gun sight to said magnet assembly, said magnet being located between said pole pieces adjacent the upper ends thereof, said magnet assembly also including a retaining block of non-magnetic material fixed to said pole pieces adjacent the lower ends thereof for retaining said permanent magnet in said assembly.

2. A mounting device in accordance with claim 1 in which the lower end of said retaining block is spaced from said gun barrel when the device is in position on said barrel whereby nicks and foreign matter on and between said retaining block and barrel will not interfere with the intimate contact of the pole pieces and said barrel.

3. A mounting device in accordance with claim 1 in which said magnet is of rectangular cross section and of substantially the same width of said pole pieces whereby a flux path of minimum reluctance is established when the device is mounted on a gun barrel.

4. A magnetic mounting device for gun sights comprising a permanent magnet assembly, said assembly including a pair of spaced pole pieces, a permanent magnet between the upper ends of said pole pieces, a separator plate of non-magnetic material above said pole pieces and magnet, a keeper of magnetic material above said separator plate, a retainer plate attached to said pole pieces and to said keeper for connecting the pole pieces to said keeper, said magnet assembly also including a retaining block below said magnet and attached to the lower ends of said pole pieces for retaining said magnet within

said assembly, said pole pieces being shaped to seat on a gun barrel, and means for attaching a gun sight to said assembly.

5. A magnetic mounting device in accordance with claim 4 in which said keeper, separator plate, and retaining block have aligned openings therethrough, and means within said openings for locating said assembly in a predetermined position on said gun barrel.

6. A magnetic mounting device in accordance with claim 4 in which there is an adjustable means carried by said mounting device for cooperation with an opening carried by said gun barrel for adjustably locating said device on said gun barrel.

7. A magnetic mounting device in accordance with claim 4 in which said keeper, separator plate, permanent magnet, and retaining block have aligned openings, a locating device within said openings, said locating device including an internally threaded bushing firmly attached to one of said parts having an opening, and a centering pin threaded into said bushing and having a portion projecting therefrom for reception within an opening carried by said gun barrel.

8. A device for attaching a sight to a firearm comprising a permanent magnet for attaching the device to the firearm by magnetic attraction, and a semi-universal joint for attaching the sight to said device, said joint including a circular split ring for surrounding the sight for clamping the same, said split ring having a convex outer surface, a concave arcuate surface on said device for receiving a portion of said ring, a member having a concave curved surface engageable with another por-

tion of the ring and attached to said device for clamping said ring tightly about said sight, said concave surfaces in planes normal to the longitudinal axis of said device having a circularity corresponding to the circularity of said convex surface, all of said surfaces in planes parallel to said longitudinal axis being curved to a radius greater than the maximum radius of said circularity whereby a semi-universal connection between said device and sight is obtained in which said sight may be positioned with its axis at a selected angle with the axis of said device when said ring is loosely clamped by said member and in which said sight may be securely clamped in said selected position when said ring is tightly clamped by said member.

9. A device in accordance with claim 8 in which the radius of said curvature is substantially twice the maximum radius of said circularity.
